UNITED STATES PATENT OFFICE.

RUDOLF M. OSTERMANN, OF EVANSTON, ILLINOIS, ASSIGNOR TO THE SUPERHEATER COMPANY, OF NEW YORK, N. Y., A CORPORATION OF DELAWARE.

INJECTOR.

Original application filed February 18, 1924, Serial No. 693,451. Divided and this application filed November 18, 1924, Serial No. 750,546. Renewed October 19, 1925.

To all whom it may concern:

Be it known that I, RUDOLF M. OSTERMANN, a citizen of the United States, and a resident of Evanston, Cook County, State 5 of Illinois, have invented certain new and useful Improvements in Injectors, of which the following is a specification.

This invention relates to injectors and more particularly to that type of injector 10 disclosed in the United States Letters Patent No. 1,342,128, granted June 1, 1920 to James Metcalfe et al. wherein is shown an injector adapted to be operated by low pressure exhaust steam; the present application being 15 a division of Serial No. 693,451, filed by me February 18, 1924.

With injectors of this type, it is necessary to reduce the amount of water admitted to the injector whenever the pressure of the 20 exhaust steam falls below a value sufficient to insure the continuity of the water jet delivered thereby; this reduction of the water is usually accomplished by means of a manually operated handle which controls 25 a movable cone within the injector. In addition to the manual regulation of the water these injectors are also provided with a supplementary live steam nozzle to assist the steam action of the low pressure steam nozzle, and while the admission of a supplementary supply of live steam is effective to assist the exhaust steam action, it necessarily 30 involves the manipulation of additional controlling means, and is subject to the further objection that it increases both the maximum and minimum water delivery of the 35 injector and therefore does not have any marked influence upon the working range of the injector.

40 It is an object of the present invention to provide in an injector of this type a new and improved construction by means of which the flow of the low pressure exhaust steam through the injector is automatically controlled by an element whose movement or 45 position would be substantially indicative of the pressure of the exhaust steam flowing to the injector.

A further object is to provide an exhaust 50 steam injector which will permit the range of water delivery to be substantially increased.

Another object is to provide adjusting means, interconnected in such a manner with

the means for automatically controlling the 55 flow of the exhaust steam, that the amount of water delivered to the injector may be varied without interfering with the automatic operation thereof.

These and further objects will be apparent to one skilled in the art to which the invention appertains by reference to the following detailed description and the accompanying drawings forming a part hereof, 60 wherein are illustrated typical examples of 65 installations constructed in accordance with the principles of my invention.

Fig. 1 is a central longitudinal horizontal section on the line 1—1 of Fig. 2 through an injector embodying my invention. 70

Fig. 2 is a side elevation of a portion of the injector shown in Fig. 1.

Fig. 3 is a section on the line 3—3 of Fig. 1.

Fig. 4 is a diagrammatic illustration of 75 an installation of the injector to a locomotive.

Figs. 5 and 6 are a sectional details of parts of the installation shown in Fig. 4.

Fig. 7 is an illustration of a modified form 80 of an installation.

Referring to Figs. 1 to 3 of the drawings the numeral 10 indicates the main casing of the injector which contains therein a main exhaust steam nozzle 11, a water cone or 85 preliminary mixing nozzle, 12, a combining nozzle 13, a delivery nozzle 14, and a further preliminary mixing nozzle 15 between the water cone and combining nozzle, all as more particularly set forth in the aforementioned patent to Metcalfe, et al. 90

The main exhaust steam nozzle 11 is movable longitudinally of casing 10 to vary the annular water inlet formed between the outer surface of the nozzle 11 and the inner 95 end of the water cone 12, and to control the amount of water drawn through the intake opening 11^a, as in the structure disclosed in said patent, but instead of the manually operated handle employed in such structure 100 to move said nozzle 11, I provide an internally screw-threaded bushing 16, rotatably mounted within the casing 10 and having a plurality of gear teeth 17 upon its outer circumference. The main exhaust steam nozzle 105 is screw-threaded, as at 18, to engage within the bushing 16. Suitable packing as indicated at 19 is inserted between the bushing

16 and casing 10, and the bushing is restricted from movement longitudinally of the casing by any suitable means.

5 A rack 20 for rotating bushing 16 is slidably mounted in a boss 21 of casing 10 and meshes with the gear teeth 17 of bushing 16, said rack being shown as a grooved rod which projects through a stuffing box 22 on said boss, and is pivotally connected, as at 10 23, to one end of a lever 24. In order to prevent rotation of the main exhaust nozzle 11, the nozzle is provided with a laterally projecting boss 25 which is suitably apertured to receive a pin or stud 26 fixed within the 15 end wall of the water cone 12.

20 Rotatably mounted within a flanged collar-like extension 27, secured, as by bolts 28, to the flanged end 29 of casing 10 is an internally screw-threaded bushing 30, having gear teeth 31 on its outer circumference with which a rack 32 engages. Rack 32 is slidably mounted within a boss 33 on the extension 27 and its projecting outer end is pivotally connected at 32^a, to the other end of 25 lever 24, the construction of bushing 30, rack 32 and boss 33 being similar to the bushing 16, rack 20 and boss 21, except that the screw-threads of the bushings 30 and 16 are opposite in direction.

30 A spider 34 terminates at its inner end in a cone-shaped surface 35, to provide a valve member which is spaced from the larger end of the inner wall of the main exhaust nozzle 11 to form an annular space through which 35 the exhaust steam passes to the said nozzle, while the other end of the spider is formed into an annular, externally screw-threaded collar 34^a to engage with the threads of bushing 30 for the purpose of moving the 40 spider 34 longitudinally of the injector to vary the size of said annular space.

45 The spider 34 forms a part of the live steam nozzle and is provided with a boss 36 having a central bore 37, through which the live steam passes, and a counter bore 38 which is slidably mounted over the live steam admission pipe 39, pipe 39 extending through the manifold 40 and being connected with the live steam conduit 41. A key 50 or pin 43 is fixed to pipe 39 and engages in a suitable key-way or slot 44 within the boss 36 of spider 34 to prevent rotation thereof while permitting longitudinal movement of the spider.

55 The inner flange of the flanged collar-like extension 27 is provided with an apertured boss 46 to which the by-pass 47 is connected, said by-pass leading a portion of the steam to the space between the water cone 12 and the further preliminary mixing nozzle 15 to provide an outer envelope of steam about the combined jet issuing from the nozzle 15 between the water cone and combining nozzle. The opening to the boss 46 from the injector 60 is located between the bushings 18 and 30

and a small valve 48 which is suitably secured to the spider 34 is adapted, when the spider 34 is moved towards the main exhaust steam nozzle, to move across and close the opening of the boss 46 to an extent substantially proportional to the throttling of the annular space between the nozzle 11 and water cone 12.

70 Means are provided for varying the positions of the spider 34 and cone 11 to regulate the range of water delivery of the injector, and such means may comprise a manually adjustable rod 57 having its inner end connected with the pivotal connection 23 of the lever 24, while its outer end is extended to any conveniently accessible point and is screw-threaded to receive the hand wheel 58.

75 Figs. 4 to 6 illustrate an installation in which the movement of the spider 34 is effected by an apparatus connected with an element of a locomotive engine, the movement of which element is indicative of variations in the pressure of the steam exhaust line. The numeral 60 indicates the valve rod of a locomotive to which is secured a collar 61. A lever 62 pivotally mounted intermediate its ends, has one end thereof pivotally connected to the collar 61, while its other end is pivotally secured to a piston rod 63 of a piston 64 slidably mounted within 80 a cylinder 65 formed on the lower part of a fluid container 66.

85 Communication between the fluid container 66 and the cylinder is furnished through a suction valve 67. A conduit 68 leads from the end of cylinder 65 to a valve casing 69 in which a pressure valve 70 is located at the delivery end of the conduit 68. One end of a pipe line 71 is secured to the valve casing 68, and its other end leads to the lower part 90 of a fluid pressure cylinder 72 mounted adjacent to the injector 10, the construction of the injector being identical with that shown in Fig. 1. An aperture 73 which is controlled by a needle valve 74 permits a portion of the fluid delivered by the pump 65 to be by-passed into the fluid container 66. The fluid pressure cylinder 72 has slidably mounted therein a plunger 75 which is connected by the plunger rod 76 with the lever 24, which lever is connected to the racks 20 and 32 of the injector, an adjusting rod 57 and handle 58 being provided all as shown in Figs. 1 to 3 inclusive. A coiled spring 77 is confined between the head of cylinder 72 105 and the plunger 75 and serves to urge the plunger against the pressure of the fluid from the pipe line 71.

110 The operation of the installation shown in Figs. 1 to 6 inclusive is as follows: The reciprocation of valve rod 60 causes the piston 64 to be reciprocated, thus withdrawing the fluid from the fluid container 66 and forcing it through conduit 68 into the pipe line 71. Needle valve 74 may be adjusted to cause a 115 120 125 130

portion of the fluid delivered by the pump to be by-passed through the aperture 73 from the valve casing 69 into the fluid container 66, it being understood that the size of the 5 aperture 73 is only sufficient to permit a small portion of the fluid to pass into the fluid container and that when the needle valve 74 is opened, it will only be opened to an extent required to regulate the pressure 10 of the fluid within the pipe line 71 and cylinder 72. For any given setting of the needle valve 74, the pressure within the pipe line 71 will obviously be closely dependent upon two factors, viz,—the main valve 15 travel, as governing cylinder cut-off, and the speed of the engine, and as these two factors are fairly indicative of the exhaust steam pressure, the pressure of the fluid within the pipe line 71 and cylinder 72 therefore 20 changes in accordance with variations of the pressure of the exhaust steam.

As the cut-off of the main valve of the engine is regulated by the reverse lever of the locomotive, Fig. 7 shows another form 25 of an installation in which the position of the lever 24 is controlled by the position of the reverse lever 80. For this purpose the center of lever 24 is connected by a link 81, to one arm 82 of a bell crank, the other arm 30 83 of which lies within the path of a lug 84 which projects outwardly from the side of the reverse lever 80. A spring 86 normally holds the arm 82 of the bell crank lever in engagement with a stop 87, as shown in Fig. 35 7. When the lever 80 is thrown to the normal forward working position, the lug 84 will engage the arm 83 of the bell crank and move the lever 24 to positions corresponding to the position of the reverse lever, thereby 40 making the positions of the racks 20 and consequently the spider 34 dependent upon the positions of the reverse lever.

During the automatic operation of the device by the cylinder and piston, the pivotal 45 connection 23 will act as a fulcrum for the lever 24 thus causing rack 32 to be moved, the rack 20 meanwhile being held stationary by the rod 57; on the other hand when the hand wheel 58 is operated the lever 24 50 will pivot upon its pivotal connection with the rod 76; with this arrangement the racks 20 and 32 will be shifted in opposite directions so that longitudinal movement of the rod 57 in one direction will simultaneously 55 cause the annular inlets for the water and

steam to be restricted, and in the reverse direction will cause the annular inlets to be increased. It will be noted that the threads of the bushings 18 and 30 are arranged to produce this movement of the nozzle 11 and 60 spider 34 respectively, and that the pitch of the threads of the bushing 30 is greater than the threads of bushing 18, so that when the nozzle 11 is moved a certain distance by the hand wheel 58 and rod 57 the spider 34 will 65 be moved a proportionately larger distance but in the same direction, this being necessary because of a variation of the quantity of water requires a greater variation in the quantity of steam supplied. 70

It will be understood that the disclosure contained herein is to be considered as illustrative and not in a limited sense and that changes, variations, and modifications may be resorted to without departing from the 75 spirit of my invention.

I claim:

1. In an injector adapted to be operated by the exhaust steam from an engine, a water controlling device, to regulate the amount of water delivered to the injector, a valve member for controlling the flow of exhaust steam through said injector, and mechanism, connected with a movable element of the engine which is indicative of the exhaust steam 80 conditions, to automatically actuate said valve member in accordance with variations in said exhaust steam conditions. 85

2. In an injector adapted to be operated by the exhaust steam from an engine, a wa- 90 ter controlling device, to regulate the amount of water delivered to the injector, a valve member for controlling the flow of exhaust steam through said injector, operating mech- 95 anism for said valve member, and mech- anism operated by the valve travel of the engine for actuating said operating means.

3. In an injector adapted to be operated by the exhaust steam from an engine, a wa- 100 ter controlling device, to regulate the amount of water delivered to the injector, a valve member for controlling the flow of exhaust steam through said injector, operating mech- 105 anism for said valve member and means comprising a fluid pressure system operated by the valve travel of the engine, for actuating said operating mechanism.

In testimony whereof I have hereunto set my hand.

RUDOLF M. OSTERMANN.
